UNITED STATES PATENT OFFICE.

SUMNER B. SARGENT, OF HUNTINGTON PARK, CALIFORNIA.

PUMP HANGER.

Application filed September 19, 1923. Serial No. 663,572.

To all whom it may concern:

Be it known that I, SUMNER B. SARGENT, a citizen of the United States, residing at Huntington Park, in the county of Los Angeles and State of California, have invented a new and useful Improvement in Pump Hangers, of which the following is a specification.

This invention relates to mechanism for connecting a walking beam or other operating member to a polish rod clamp for producing operation of a well pump, and an object of the invention, in general, is to provide for adjustment between the walking beam and polish rod so that the stretch of the sucker rods can be compensated for.

Another object is to provide for automatic release if part of the hanger mechanism should break while in use, thus avoiding injury to the polish rod, hanger or other parts.

Another object is to facilitate the employment of cables or rods, at the option of the operator, for connecting the polish rod clamp to the walking beam.

Other objects and advantages will appear in the subjoined detailed description.

The accompanying drawings illustrate the invention:

Figure 1 is a side elevation of a pump hanger embodying the invention, a walking beam and Samson post also being shown.

Fig. 2 is an elevation from the right of Figure 1.

Fig. 3 is an enlarged side elevation of one of the links, a fragment of one of the rods and the nut for connecting the link and rod.

Fig. 4 is an edge view of Fig. 3 from the left thereof.

Fig. 5 is a plan section on the line indicated by 5-5, Figure 3.

Fig. 6 is an enlarged fragmental plan view, partly in section, from the line indicated by 6-6, Figure 2.

Fig. 7 is a sectional elevation on the line indicated by 7-7, Figure 6.

Fig. 8 is a fragmental elevation of a modified construction for connecting the pivotally suspended arm with the rods.

Fig. 9 is a side elevation of Figure 8.

Fig. 10 is a plan section on the line indicated by 10-10, Figure 8.

Fig. 11 is a fragmental section on the line indicated by 11-11, Figure 8.

First referring to the construction illustrated in Figures 1 to 7 of the drawings, an operating member to which the pump hanger connects is indicated at *a*, being, in this instance, a walking beam fulcrumed at *b* on a Samson post *c*. The walking beam *a* is provided with the usual slot *d* in its end to accommodate an arm *8*, that is provided with a bearing *9* through which projects a shaft *10*. The shaft *10* is mounted at its opposite ends in boxes *11* which are secured by lag bolts *12*, or other suitable devices, upon the upper face of the walking beam, *a*, on opposite sides of the slot *d*. Thus the arm *8* is pivotally suspended from the walking beam.

The lower end of the arm *8* is provided with an eye *13*, the lower wall of said eye being arcuate or upwardly convex on the inside as indicated at *14*. Engaging the arcuate portion *14* is a cross arm *15* which has an arcuate recess *16* fitting the arcuate portion *14*. Thus the cross arm is tiltably mounted on the arm *8*.

The cross arm *15* is held assembled with the arm *8* by a bolt *17* which extends transversely of the eye *13* a slight distance above the cross arm, the distance being just sufficient to permit of tilting of the cross arm with respect to the arm *8*. The bolt *17* also engages and supports within the eye *13* a latch member *18*, the upper face of which seats against the upper wall of the eye.

The latch member *18* is releasably engaged by a pair of oppositely arranged latch members *19*, which, in turn, engage the outer faces of nuts *20* screw-threaded on rods *21* that are accommodated in slots *22* in the opposite ends of the cross arm *15*. The connection between the latch members *18*, *19*, in this instance, is constituted by sockets *23* in the latch member *18* and lugs *24* projecting from the latch members *19* into said sockets, as clearly shown in Figure 7. The outer ends of the latch members *19* are slotted at *25* to accommodate the upper

ends of the rods 21. The latch members 19 have at their outer ends downwardly projecting lugs 26 which engage the outer faces of the nuts 20 to prevent said nuts from turning and sliding outwardly and off of the cross arm 15. The nuts 20 constitute one form of devices that may be employed to engage the rods and slots on the cross arm.

10 Though not absolutely necessary, it is advisable to hold the latch members 19 toward the nuts 20 to insure against jarring loose of the latch members 19 from the nuts 20. Any suitable means may be provided 15 for this purpose and, in this instance, the rods 21 are provided above the latch members 19 with nuts 27 and between the nuts 27 and latch members 19 with coil springs 28 that press upon the latch members 19 to yieldingly hold them in engagement with the nuts 20. Thus the latch members 19 are loosely connected with the nuts 20 and the advantage of this will appear hereinafter.

25 The lower ends of the rods 21 are screw-threaded into split nuts 29 which are accommodated in links 30, upward and downward movement of the nuts being limited, respectively, by upper shoulders 31 and lower shoulders 32 in the link. The side walls of the links prevent turning of the nuts 29. The nuts 29 are clamped upon the rods 21 by bolts 33 which are positioned transversely to the split 34 in the nuts. The 35 nuts 20 and upper ends of the rods 21 have their screw-threads the reverse of the screw-threads of the nuts 29 and lower ends of the rods, so that the rods and nuts together constitute, in effect, turn buckles, adjustment occurring simultaneously at both ends of each rod as the rod is turned.

40 The upper ends of the links 30 are formed with tubular portions 35 through which the rods 21 extend. The lower ends of the links 45 constitute bearings 36 to receive the opposite ends of a bar 37, there being cotter pins 38 extending transversely through the bar 37 to prevent said bar from pulling out of the links. The bar 37 is for the purpose of 50 supporting the polish rod clamp, not shown.

55 From the foregoing it will be clear that the latches 18, 19 connect the arm 8 to the rod engaging devices 20 when the cross arm is approximately horizontal, and that one of the latches is released by tilting of the cross arm to release the associated rod-engaging device and permit it to slide from the cross arm.

60 The upper end of the arm 8 is provided with an eye 39 above the bearing 9 so that the arm can be readily engaged by a tackle hook when it is desired to raise the pump hanger higher than the walking beam can lift it.

65 Assuming that the pump hanger is con-

nected with a polish rod and with an operating walking beam and that stretching of the sucker rods has occurred, a Stillson wrench will be applied to the rods 21 to turn said rods in a direction to reduce the distance between the cross arm 15 and bar 37. If one of the rods 21 should break, the weight of the sucker rods coming upon only one end of the cross arm 15 will tilt downwardly the end of the cross arm that is connected with the unbroken rod, and when this occurs the outer end of the cooperating latch member 19 will also tilt downwardly, thus prying its lug 24 out of the cooperating socket 23 and releasing the latch. When the latch member 19 is thus released, it will be clear that the associated nut 20 will slide off of the cross arm 15, thus disconnecting said cross arm from the polish rod and the operation of the polish rod will then cease. 85 This will avoid any injury to the pumping apparatus that might otherwise be caused by continued reciprocation of the polish rod more or less eccentrically as would result if the cross arm 15 and bar 37 were not entirely disconnected.

When it is desired to employ cables between the arm 8 and the polish rod, instead of the rods 21 and the other parts cooperating with said rods, the bolt 17 will be removed and the cross arm 15 will then be taken off with all of its cooperating parts, and a suitable cable or cables, not shown, will be rove through the eye 13 so that the bight of the cable will rest upon the arcuate portion 14. The lower ends of the cables may be connected with the polish rod clamp by any suitable means, one form of such means being disclosed in my copending application for patent filed Sept. 19, 1923, 100 Serial No. 663,571.

Other suitable means than those described above may be employed for connecting the opposite ends of the cross arm to a polish rod clamp and other devices than the latches 110 and nuts 20 may be used within the scope of some of the appended claims without departing from the spirit of the invention.

Instead of the means described above for connecting the walking beam to the rods, 115 there may be employed the modified construction illustrated in Figures 8 to 11, inclusive. In the illustrations of the modified construction, those parts that are functionally the same as those previously described herein will be indicated by the same reference characters with the addition of an index letter "a". The arm 8^a is provided with the eye 13^a of which the lower end wall is arcuate at 14^a so that, if desired, the cross arm 15 may be employed the same as with the arm 8 or the bight of the cable may rest upon the arcuate portion, as previously referred to. The rods are indicated at 21^a and adjustably engage nuts 20^a 120 at 125 125 and 130 adjustably engage nuts 20^a 130

which are provided with laterally extending abutments 42, that are circular in cross section in this instance, and that seat upon the tips of a cross arm or cross arms 15^a.
 5 The nuts 20^a and their abutments 42 constitute one form of devices engaging the rods and slidably mounted on the end portions of the cross arms. The cross arms 15^a are mounted on the opposite ends of a
 10 shaft 48 which extends through a bearing 40 at the lower end of the eye 13^a, the top of said bearing constituting the arcuate portion 14^a. The cross arms 15^a are fixed by pins 41 or otherwise to the shaft 48 and by
 15 said shaft are fulcrumed or tiltably mounted on the arm 8^a. The shaft 48 is free to turn in the bearing 40 but, normally, the cross arms 15^a are in horizontal position because of the rods 21^a pulling equally on opposite
 20 ends of the cross arms.

To prevent the abutments 42 from sliding off the cross arms, when the cross arms are approximately horizontal, there is provided an arcuate member 43 extending
 25 through the eye 13^a and mounted on a pin 44 that extends transversely of the eye, the opposite ends of the arcuate member 43 constituting latch members and being positioned to engage the outer faces of the
 30 abutments 42 which thus constitute other latch members that cooperate with the first latch members 43. The under face of the arcuate member 43 is an arc whose radius is struck from the axis of the shaft 48. To
 35 prevent oscillation of the arcuate member 43 about the axis of the pin 44, said arcuate member is provided with an upwardly extending ear 45 having a notch 46 in its upper end, and engaging in said notch is an
 40 abutment 47 projecting from the upper end wall of the eye 13^a.

With the construction just described, it will be readily understood that breaking of one of the rods 21^a will permit all of the
 45 weight suspended from the other rod to tilt the cross arms 15^a about the axis of the shaft 48 so as to cause the abutment 42 associated with the unbroken rod to lower to a position below the arcuate member 43 so
 50 that said abutment will slide off of the tilting cross arms and thus disconnect the arm 8^a from the pump. With this brief explanation the operation of the construction shown in Figures 8 to 11 will be apparent
 55 because of its similarity in some respects with the construction shown in Figures 1 to 7.

I claim:

1. A pump hanger comprising an arm
 60 having an eye, the lower wall of the eye being upwardly convex, means to pivotally suspend the arm from an operating member, a cross arm resting on the lower wall of the eye, and means to retain the cross arm in the eye.

2. The link described having upper and lower shoulders inside thereof to accommodate a nut therebetween, and having a box at one end and a tubular portion at its opposite end.

3. A pump hanger comprising an arm having an eye, the lower wall of the eye being arcuate, means to pivotally suspend the arm from an operating member, a cross arm having an arcuate recess fitting the arcuate portion of the first arm, and means to connect the opposite ends of the cross arm to a polish rod clamp.

4. A pump hanger comprising rods, means to connect the rods at one end to a polish rod clamp, and means to connect the rods at the other end to an operating member, one of said means operating upon the breaking of one of the rods to release the other rod.

5. A pump hanger comprising rods, means to connect the rods at one end to a polish rod clamp and operating upon turning of the rods to relatively adjust the rods and clamp, and means to connect the rods at the other end to an operating member and operating upon turning of the rods to relatively adjust the rods and operating member.

6. A pump hanger comprising a cross arm, means to tiltably connect the cross arm to an operating member, rods, devices engaging the rods respectively and slidably mounted on the end portions of the cross arm, and latches connecting the arm connecting means to the rod engaging devices when the cross arm is approximately horizontal, one of the latches being released by tilting of the cross arm to release the associated rod-engaging device and permit it to slide from the cross arm.

7. A pump hanger comprising an arm, means to pivotally suspend the arm from an operating member, a cross arm tiltably connected with the first arm and provided at its opposite ends with slots, rods in the slots, nuts on the rods slidably mounted on the cross arm, latches detachably connecting the nuts to the first arm and releasable by tilting of the cross arm, and means to connect the rods to a polish rod clamp.

8. A pump hanger comprising a tiltably mounted cross arm, rods, and means connecting the rods to the cross arm when the cross arm is approximately horizontal and operated by tilting of the cross arm to release the rods.

9. A pump hanger comprising a tiltably mounted cross arm, rods, devices engaging the rods respectively and slidably mounted on the end portions of the cross arm, and means to prevent the rod-engaging devices from sliding off of the cross arm when the cross arm is approximately horizontal, said means releasing one of the rod-engaging

devices and permitting it to slide from the cross arm when the cross arm is tilted.

10. A pump hanger comprising an arm, means to pivotally suspend the arm from an operating member, a cross arm ful-

crumed on the first arm, rods, devices engaging the rods respectively and slidably mounted on the end portions of the cross arm, and an arcuate member mounted on

the first arm and having its ends engaging the outer faces of the rod-engaging devices to prevent said devices sliding off of the cross arm when said cross arm is approximately horizontal.

Signed at Los Angeles, California, this 15
7th day of September 1923.

SUMNER B. SARGENT.
